UNITED STATES PATENT OFFICE.

HENRY M. BEECHER, OF NEW HAVEN, CONNECTICUT, ASSIGNOR OF ONE-HALF TO CHARLES S. MERSICK, OF SAME PLACE.

FENCE-POST.

SPECIFICATION forming part of Letters Patent No. 255,714, dated March 28, 1882.

Application filed October 1, 1879.

To all whom it may concern:

Be it known that I, HENRY M. BEECHER, of the city and county of New Haven, and State of Connecticut, have invented certain new and useful Improvements in Fence-Posts, of which the following is a specification.

In the accompanying drawings, Figure 1 is a side elevation of a fence-post which embodies my invention, and Fig. 2 is a plan view of the same.

I form both the upright A and the feet B B' of angle-iron. The feet are curved in opposite directions, and are riveted or otherwise rigidly secured together, with the corners of the angle-irons toward each other, as shown. The foot B' is formed on the end of the upright A in one and the same piece. A portion of one of the flanges of each foot is bent over and out into substantially the same plane as its fellow-flange to form the flukes a a. The foregoing construction makes a very inexpensive and at the same time a light but very strong and rigid post, which will stand firm in the ground on account of being supported in all directions by the flanges of the angle-irons.

The flukes a a, it will be seen, are much broader than the width of the feet and project from the ends thereof, whereby they are in a position and large enough to furnish great resistance to the post being racked sidewise in the direction which the feet spread. The flanges of the angle-iron, when the iron is curved and placed together with the angular corners of the two feet toward each other, furnish a greatly increased bearing or bracing surface to support the post in every possible direction, while at the same time the groove formed by each angle-iron is open at the top for the whole length of both feet, so as to be conveniently filled and packed with earth in tamping around them.

I have herein described the feet of the post as rigidly secured together; but, if desired, they might be jointed or hinged, as shown in another application of mine now before the Patent Office. An acceptable post might be formed with the feet made of angle-iron curved and placed together, as shown and described, but without any portion of the flanges turned over

to form the broad flat flukes a a; but a better 50 post is produced when the flukes a a are present.

I am aware that prior patents show the use of angle-irons for fence-posts which are straight throughout their entire length, including the 55 foot portion for entering the ground; but so far as I know a curved angle-iron was never before employed for any part of a fence-post. Neither has any fence-post ever been made or shown having supporting flanges standing in 60 such relation to the foot of the post as they do in my post.

I am aware that a prior patent shows a divided upright for a post, the parts being hinged together, and each part having a curved but flat 65 foot rigidly secured to it, but secured to its companion only by the hinge. Another patent describes and shows two straight bars of iron for forming a post by inserting them into a proper base when in the form of an X, and 70 then bending the upper arms of the X together and binding them to form the upright of the post, while the bottom of the X forms the feet thereof. Another patent shows a post with the foot in the form of a tapering screw adapted 75 for screwing into the ground. Another patent shows a split tube for the foot of a post, the ends of each splint being pointed and turned slightly outward, so that the splints would spread out into a divaricated foot when 80 the split tube was forced into the ground. Another patent shows an angle-iron for the straight upright portion of a post, but not for the foot portion, and without any part of the angle-iron being curved; and, finally, another patent shows a post made of a straight flat bar of 85 iron, with a portion thereof bent off edgewise at an angle, so as to form a straight leg standing obliquely to the upright. The lower end was bent flatwise to one side and at right angles to the upright to form a foot. A like leg with a like foot turned in the opposite direction was welded to the foot of the upright, all of which prior devices are hereby disclaimed.

I claim as my invention--

1. A fence-post the foot of which consists of two curved pieces of angle-iron standing in opposite directions, with the corners of the an-

gles facing each other, the parallel flanges of said two pieces being placed one upon the other at their junction and secured together, substantially as described, and for the purpose specified.

2. In a fence-post, the foot formed of curved angle-iron and having a portion of one of its

flanges turned over into substantially the same plane as its fellow flange, substantially as described, and for the purpose specified.

HENRY M. BEECHER.
